UNITED STATES PATENT OFFICE.

GERHARDT F. SCHWARTZ, OF ST. LOUIS, MISSOURI.

SAFETY CONTROL FOR AUTOMATIC GAS APPLIANCES.

Application filed February 25, 1921. Serial No. 447,664.

To all whom it may concern:

Be it known that I, GERHARDT F. SCHWARTZ, a citizen of the United States, and resident of the city of St. Louis, in the 5 State of Missouri, have invented certain new and useful Improvements in Safety Controls for Automatic Gas Appliances, of which the following is a description.

This invention relates to improvements 10 in safety control for automatic gas appliances and has for an object to effect the closing of the main gas supply valve in automatic gas appliances, such as an automatic gas water heater, gas furnace, gas 15 steam boiler, radiator, gas stove, etc., in the event that the flame at the pilot burner be extinguished for any reason. To this end the invention proposes the use of a thermostat arranged so as to actuate either directly 20 or through the agency of suitable mechanism, the main valve, which controls the supply of gas to the main burner of the furnace water heater or the pilot burner when the flame of the pilot burner is ex- 25 tinguished.

Other objects will appear and be better understood from that embodiment of my invention of which the following is a specification, reference being had to the accompanying drawing, forming a part thereof and in which:

Figure 1 is a side elevation of one form 35 of the invention in use. Figure 2 is a detail side elevation of a modified form of control. Figure 3 is a side elevation of a further modification. Figure 4 is a detail side elevation of a still further modification. Figure 5 is a detail of a modified form of valve operating device. Figure 6 is a de- 40 tail side elevation of a modification wherein the thermostat is disposed horizontally. Figure 7 is a detail end elevation of Figure 6. Figure 8 is a view similar to Figure 7, showing a modification thereof. Figure 9 is a detail side elevation of a still further 45 modified form. Figure 10 is a detail side elevation of a pilot burner, showing further modification of the invention as a circuit closer. Figure 11 is a view similar to Figure 10 or a still further modified form of 50 circuit closer. Figure 12 is a detail plan of modified form of thermostat. Figures 13 and 13^a are detail plans of a still further modification of thermostat. Figure 14 is a diagrammatic view of a combined electric and 55 thermostatic control. Figure 15 is a

view similar to view 14 of another modified form of electric and thermostatic control. Figure 16 is a detail side elevation of a still further modified form of electric and ther- 60 mostatic control. Figure 17 is a detail side elevation of modified form of thermostatic and mechanical control. Figure 18 is a fur- 65 ther modification of thermostatic and me- chanical control. Figure 19 is a still fur- 70 ther modification of thermostatic and me- chanical control. Figure 20 is a perspective of the support sleeve or collar for the ther- mostatic element used in all of the above modifications.

In the form of the device illustrated in Figure 1, the tube 5, of the pilot burner A, carries at its upper end the usual tip 6, below which is arranged the sleeve or collar 7, which is suitably secured to the tube 5, in 75 any preferred manner, as with the set screw 8. The material for the collar or sleeve 7 is preferably metal and a good conductor of heat, and the disposition of the sleeve is such that the same will receive an 80 amount of heat directly from the flame at the tip 6, and will also receive heat con- ducted thereto by tube 5. The laterally ex- 85 tends portion 9, of sleeve 7, is suitably provided with a socket which receives the upper end of the thermostat 10, which ele- 90 ment is herein shown, as an oblong piece made up of two metals having different co- 95 efficients and extending to the ledge 11, se- cured to and extending laterally from tube 5, and underlying the extension 9. Any combination of well known metals may be employed for thermostat 10, as for instance, brass and steel. With the thermostat ar- 100 ranged as shown, brass layer on outside, steel on inside, known commercially as thermo- static metal; the lower end thereof curves toward tube 5, when the thermostat is ex- 105 panded by the action of heat. The ledge 11 forms a support for an angular shaped arm 12. When the thermostat 10 is in its nor- 110 mal position and extends vertically down- ward the lower end thereof occupies the space on one side of which the latch 12 is dis- posed when the parts are positioned as shown in Figure 1, so that the lower end of the thermostat when moving outwardly, upon cooling, operates to unlatch the latch 12 from ledge 11. An arm 14, which is piv- 115 oted at one end to latch 12, is pivotally con- nected at its opposite end to a suitable sup- port which may be a portion of the appli-

ance B as shown. A ring loosely receives the arm 14 and serves for connecting one end of a suitable supporting element, such as a chain or cable 16, to the arm. The chain or cable passes through the handle 17 of the valve 18, which controls the flow of gas to the appliance B and burner A and is connected at its lower end to a weight 19. A disc 20, of a diameter greater than the opening in the handle 17, for cable 16, is disposed between the handle 17 and arm 14, so that upon disengagement of the latch 12 from ledge 11, followed by downward turning or dropping of arm 14 and lowering of cable 16, under action of weight 19, disk 20 will strike arm 17, whereupon the continued pull of weight 19, will result in turning the handle 17 and closing valve 18.

In the modified form shown in Figure 2, 20 the turning of the valve handle 21 is accomplished directly by a bell crank lever 22, pivotally connected at its opposite ends to handle 21 and arm 23 respectively. When latch 24 is disengaged by the thermostat, as described in connection with Figure 1, arm 23 and the parts connected thereto are moved downwardly by a weight 25 to which is connected a carriage in the form of loop 26, which embraces arms 23 and bell crank 22, 30 and which is provided with a sheave 27, adapted to roll upon the side of arm 23, or the wire or loop 26 can be attached permanently to arm 23.

In the form illustrated in Figure 3, the 35 thermostat 28, is pivotally connected at its lower end to an arm 29, which is supported in the horizontal by a support herein shown as a ringbolt 30, or its equivalent, which loosely receives the free end of arm 29, and which is formed with a ledge 31, on which is disposed a wheel or roller 32, supporting a flexible element such as a length of cable 33, that extends through valve handle 34 and is attached at its lower end to a weight 35, 40 and which is further provided at a point between the ledge and the handle with a disc 36. In connection with this modification it will be observed that when the thermostat assumes its normal position, the arm 29 will be moved axially and strike the wheel 32, causing the same to disengage by rolling from ledge 31, whereupon valve handle 34 will be turned as previously described.

In the modified form shown in Figure 4, 55 a ringbolt 37 supports one end of a tubular arm 38, the opposite end of which receives ledge 39, extending laterally from burner tube 5 and disposed at the lower end of thermostat 40. With this construction the 60 thermostat 40 disengages arm 38 from ledge 39, whereupon ring 41 surrounding arm 38 moves downwardly with the arm and lowers disc 42, carried by cable 43, into engagement with valve handle 44, after which handle 44 is turned by the pull of weight 45.

In Figure 5 the parts are the same as described in connection with Figure 4, except that cable 46 is attached to the end of valve handle 47, with this construction the disc 42, described in connection with Figure 4, 70 is omitted.

In Figure 6, the sleeve or collar 48 on tube A is constructed with a lateral socket so that thermostat 49 is disposed horizontally. In this connection, and as shown in Figure 7, 75 the angular shaped extension 50 pivoted to arm 51, is engaged and supported by a thermostat 49, when the same is flexed by the heat of burner "A", but disengages from the extension 50, in moving to its normal position, whereupon latch 51 and the parts connected thereto, which may correspond to those described in connection with Figures 1 and 2, but not herein shown, will operate as previously described.

In the modified form, illustrated in Figure 8, the parts are the same as those described in connection with Figure 7, except that a ledge 52, supports an angular shaped extension 53 to arm 54 and the thermostat 90 55 operates to disengage extension 53, by moving into contact therewith.

In the modified form shown in Figure 9, the sleeve or collar 56, connected to burner tube A, transmits heat to thermostat 57, 95 which is secured at one end to collar 56, and at its opposite end is pivotally connected to a rock arm 58, carried by standard 59, secured to a shelf 60, extending outwardly from tube A. The angular shaped extension 61 of arm 62 engages one end of rock arm 58, supported by spring 63 the thermostatic element 57 in this instance is formed of a length of suitable wire. In this connection the thermostatic element 57 105 will contract in the absence of heat and thereby turn rock arm 58, against the pressure of a sprint 63 and disengage extension 61, and cause the parts connected thereto, which may be any of those described in 110 connection with Figures 1 to 5, to operate as previously described.

In connection with form shown in Figures 10 and 11, the thermostat 63 operates upon the cooling of burner A to close an 115 electric circuit by moving into contact with the terminals 65 and 66, which are connected to the circuit wires 67 and 68. In connection with Figure 10 the terminals 65 and 66 are carried by an insulating body adapted 120 to be connected to the tube of burner A, and in this connection it will be noted that the lower end of the thermostat is arranged so as to curve outwardly from the tube under the influence of heat from the burner.

In Figure 11 the thermostat is arranged so as to operate as described in connection with Figure 10 and the terminals 65 and 66 are supported by one of the sections 69, of a ledge which is insulated as indicated by 125

70, from a section 71, secured to the tube of burner A. In this connection the tube of burner A will be sectional and the upper section of that shown in Figures 10 and 11 5 will be suitably insulated from the lower section, not shown.

In Figure 13 the thermostat circuit closer is made up of wire or band sections 115 and 116, which are normally curved and tend 10 to straighten under the action of heat. These sections may extend horizontally, vertically or be otherwise disposed, as desired or found necessary, and are connected at one end to the collar 113, secured to tube 5 15 and constructed like collar 9, except that revision is made in the form of the socket for the bent in sections 115 and 116, 115^a and 116^a are intended to form contact points or circuit closers. Sleeve 118 or non-con- 20 ducting material may receive the ends of sections 115 and 116 which are connected to conducting wires 67 and 68; or the sleeve 118 may be omitted. In any event and when the ends of sections 115 and 116 move 25 into contact in the absence of heat from the burner, the circuit wires 67 and 68 will be closed. The connection between the sections 115 and 116 and collar 117 will be such 30 that the said sections will be electrically insulated from the collar.

In the form shown in Figure 12 the thermostat consists of a horizontally disposed element 119, corresponding to one of the sections 115-116 or thermostatic metal 10 35 in curved form the said section 119 being arranged to disengage a latch, as for instance the latch 12, or to close an electric circuit in which event the thermostat will be insulated from collar 120 and be suitably 40 connected to a conducting wire and operatively arranged to affix terminal shown diagrammatically in Figure 12 and indicated by 121.

Included in the electric circuits contracted by the thermostat shown in Figures 45 10 and 11, may be an electromagnet 72, as shown in Figure 14, or solenoid 73, as shown in Figure 15. The armature 74, of magnet 72, is connected to the valve stem 75 and 50 the core 76 of solenoid 73, is connected by a flexible element 77, trained over pulleys 78 to the handle 79. The source of electric 55 energy may be a battery of cells as indicated by 80, which the circuit wires 81 and 82 connect with the wires 67 and 68. Obviously the closing of this electric circuit will energize the electro magnet 72 or the solenoid 73, in which instance the valves 75 or 79 will operate to close and cut off the 60 supply of gas to the burner. If desired, or when found necessary, a suitable audible signal, such as an electric bell 83 and a transformer 83' may be included in the electric circuit for the purpose of giving an 65 audible signal on the closing of the valve.

In the modified form of circuit closers shown in Figures 14, 15 and 16, a switch arm is operated by the thermostat as distinguished from the structure previously described wherein the thermostat functions 70 as the switch arm. In Figure 14 the switch arm is pivotally connected to a support 85 which may form part of the appliance B and is normally held in spaced relation to the terminals of the wires 67 and 68 by a 75 spring 86. A thermostat 87, in the form of a length of suitable wire, is attached at one end to lower end of arm 85 and extends over a pulley 88, supported by a boss 89, on the tip 6 of the pilot burner. The wire 87 extends downwardly through an opening in tip 6 and is attached to an adjusting screw 90, so that switch arm 84 may be adjusted 80 into contact with the terminals of wires 67 and 68 when the temperature of the wire 85 is normal. With this construction spring 86 will move the arm 84 to the position shown when wire 87 is attenuated by heat. Thermostat 90 in Figure 15 and that indicated by 91' in Figure 16 operate in the 90 manner described for thermostat 87, the thermostat 90 being arranged vertically and extending through the tip 6 of the pilot and secured at its upper end to a convenient portion of the appliance A, a pivot 91 connecting the lower end of the thermostat to arm 92, pivoted to tube 5. Thermostat 91' is disposed horizontally and bears on the tip 6 with its inner end secured to a bracket 93, carried by tube 5 and its outer end extending through the appliance B and in operative relation to a vertically disposed switch arm 94, similar to the switch arm 84. Spring 95 normally holds arm 94 in contact with the terminals of wires 67 and 68 and the spring 96 is disposed so as normally to hold the free end of arm 92 in contact with the terminals of wires 67 and 68. 95

In connection with the structure shown in Figure 15 spring 96 operates to move arm 92 to close the circuit when thermostat 90 contracts in the absence of heat from burner A, whereas in Figure 16 thermostat 91, while undergoing contraction co-operates with spring 95 to move arm 94, so as to close the 100 electric circuit. 110

The form shown in Figures 17, 18 and 19, the closing of the valve indicated by 97 in Figures 17 and 19 is effected by a lever 98. In the form shown in Figure 17 the lever 98 is disposed in the horizontal and fulcrumed on a bracket arm 99, carried by tube 5. Thermostat 100 is secured to sleeve or collar 101 which corresponds to sleeve or collar 9, in Figure 1, and is pivotally connected at its lower end to lever 98. The stem 102 of valve 97, which is herein shown as a globe valve is recessed and disposed in a casing 103, which has oppositely disposed recesses 125 190

104, which loosely receive the free end portion of the lever 98, which extends through the recesses of the valve stem. The thermostat 100 operates when heated to elevate the free end portion of lever 98 and valve 97 against the action of spring 103, which operates to move valve 97 to its seat and maintain it there when thermostat 100 undergoes contraction in the absence of heat from the burner A.

In principle the form shown in Figure 18 is identical with that shown in Figure 17. Certain of the parts are, however, constructed differently from corresponding parts in Figure 17, in that thermostat 106 is tubular and surrounds tube 5 and operates when heated on the annular inner end 107 of lever 108, which surrounds the burner tube 5. Lever 98 in Figure 19 is disposed 20 in the vertical and is fulcrumed on a bracket 109, forming part of the bracket 110, carried by tube 5. Thermostat 111 is disposed horizontally and extends through an opening in sleeve 112, connected at its outer end with lever 98, and its inner end secured to the bracket 110, or the appliance B. The connection between the lower end of the lever and the valve 97 is similar to that described in connection with Figure 17, except the 20 valve and the casing therefor, together with the spring 114, are disposed horizontally. With this construction the lower end of the lever is moved outwardly and spring 114 cooperates therewith to seat the valve 97 when thermostat 111 contracts in the absence of heat from the pilot burner.

In the several embodiments shown the device operates automatically when the flame is extinguished at the pilot burner, to close the main gas valve so that in automatic water heaters and the like, the flow of gas to the main burner will be cut off in the event that the flame of the pilot burner is extinguished accidentally.

I claim:

1. In combination with a burner having a supply pipe with a valve therein, a thermostat placed relatively to the burner and moving consequent upon the cold or heated condition of the burner, a releasable catch means placed to be tripped by said thermostat when cold, and a weight normally held elevated by said catch until tripped, and having initially slidable connection with said valve whereby to enable the weight to acquire momentum to operate the valve, said weight having means associated therewith for subsequently causing the valve to move

with the weight at an advanced stage of the movement of the weight.

2. In combination with a pilot valve, a fuel supply pipe therefor, and a valve in the pipe having a controlling member associated therewith, a thermostat placed close to the burner and adapted to move in one direction in the heated condition of the burner when the pilot burner is lighted and to react in the opposite direction on the cold condition of the burner consequent upon the extinguishing of the light, a weight, means to support said weight in a potential position, said means adapted to be released upon the reaction of the thermostat due to the cold condition, said weight having an initial relative movement with respect to the valve controlling member and having means associated therewith to subsequently set up a positive connection between said weight and said valve controlling member whereby to utilize the momentum of the weight to close the valve when the pilot burner is extinguished.

3. In a safety control for gas appliance, the combination of a burner, a normally open valve controlling the supply of gas to the burner, a thermostat disposed to be affected by the heat of the burner, means for automatically closing said valve, a supporting means for said last named means adapted to be released by the action of said thermostat, said supporting means adapted to slidably receive said first named means to permit the latter to have an initial movement not effecting the valve, said valve closing means having connection to the valve whereby the final movement of such means will operate to close the valve abruptly.

4. In a safety control for gas appliance, the combination of a pilot burner, a normally open valve for supplying gas to the burner, an operating member for the valve, a weight, a flexible supporting connection attached to the weight and sliding through said member, said supporting connection having means thereon normally spaced above the member for striking said member to close the valve on the descent of the weight, and a thermostat associated with the burner for controlling the releasing of the weight.

In testimony that I claim the foregoing as my invention, I have signed my name hereunder.

GERHARDT F. SCHWARTZ.
